UNITED STATES PATENT OFFICE.

DAVID S. KENNEDY, OF BROOKLYN, NEW YORK, ASSIGNOR TO MERGENTHALER
LINOTYPE COMPANY, A CORPORATION OF NEW YORK.

TYPOGRAPHICAL MACHINE.

1,136,535.

Specification of Letters Patent. Patented Apr. 20, 1915.

Application filed October 23, 1913. Serial No. 796,745.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to form 20 a slug or linotype against the matrices which produce the type characters thereon, and the matrices thereafter returned through distributing mechanism to the magazine from which they started. More particularly, it relates to such machines when equipped with a plurality of fonts of matrices, any one of which may be brought into action at will, and is designed to supplement the selected main font by any one of several 25 auxiliary fonts capable of simultaneous employment therewith. Preferably and more specifically, the main fonts are contained in a plurality of magazines, any one of which may be brought into operative relation to the assembling devices, when desired, and the auxiliary fonts are contained in a plurality of supplemental magazines, any one of which may be similarly brought into operation, at will. The practical effect of 30 this arrangement is to permit the simultaneous employment of any pair of magazines chosen respectively from the separate series. I also believe myself to be the first to employ a plurality of supplemental magazines, 35 any one of which may be brought into operation simultaneously with a main magazine, irrespective of whether the latter be single or one of a plurality. The new arrangement also includes improvements in 40 the means for shifting and locking the magazines of both sets, as well as other features which will be described in the specification and finally pointed out in the claims.

45 In the accompanying drawings, I have 50 shown my invention as applied to the com-

mercial "Model 8" linotype, substantially as presented in the application for Letters Patent of John R. Rogers, Serial No. 624,426, filed May 1, 1911, wherein the magazines are movable with reference to the 60 assembling mechanism; but it will be understood that it may be also adapted to machines like the commercial "Model 9" linotype, wherein the magazines are stationary and a portion of the assembling devices is 65 shifted. Further, it will be obvious that many changes and variations may be made in the form and adaptation of my invention, which will still be comprised within its 70 spirit. Thus, it may similarly be applied to other forms of typographical machines, such as typesetters, typecasters and the like, which handle type or dies, instead of matrices. Generally speaking, I desire it to be 75 understood that I do not limit myself to any specific form or embodiment, except in so far as such limitations are specified in the claims.

80 Referring to the drawings: Figure 1 is a side view, partly broken away, of a portion of a linotype machine, having my invention applied thereto; Fig. 2 is a front view thereof; Fig. 3 is a diagrammatic view, indicating the manner in which any pair of magazines selected from the respective sets 85 may be brought into simultaneous operation; Fig. 4 is a detail, partly in section and broken away, showing the connecting mechanism, etc., for both sets of magazines; Fig. 90 5 is a diagrammatic view of a modification, indicating the manner in which a selected auxiliary magazine may be brought into simultaneous operation with a single main magazine; Fig. 6 illustrates another modification, embodying a plurality of short auxiliary magazines, and showing them in front and side elevation respectively; and Fig. 7 95 is a section on the line 7—7 of Fig. 1, illustrating the arrangement of the locking means for the several series of magazines. 100

105 As in the Model 8 linotype, or as presented in the previously mentioned application, a plurality of shiftable magazines D is so mounted and arranged that by the operation of the handle J¹, any selected one thereof may be brought into relation to the assembling devices. The matrices are released from the active magazine by the manipulation of the keyboard P, and pass onto the belt Q, whereby in turn they are delivered 110

into the assembler Q¹. The parts so far described, and except as hereinafter specified, may be of any approved construction and mode of operation, and in themselves constitute no part of the present invention.

Arranged at the side of the magazines D is a series of auxiliary or supplemental magazines E, so mounted and arranged that by the operation of the same handle J¹, any selected one thereof may be similarly brought into relation to the assembling devices. The supplemental matrices are released from the active magazine E by the manipulation of the keyboard P¹, and pass onto the before mentioned belt Q, it being observed that the latter is extended so as to receive matrices from both the selected main magazine D and the selected supplemental magazine E. The main matrices are returned to the magazine D in the usual manner by the distributing mechanism R, which is extended longitudinally so as also to deliver the supplemental matrices to the magazine entrance S and thence to the auxiliary magazine E. It will be noted that due to the previously described construction and mounting of the parts, I am enabled to select any desired pair from the respective series of magazines and bring them into operation simultaneously, so that matrices may be released from both and assembled in the same line, as distinguished from the arrangement embodied in the Model 8 and Model 9 linotypes, wherein only one of the plurality of magazines is in action at a time.

The means for shifting the respective series of magazines are best illustrated in Figs. 1, 2 and 4. The main magazines D are mounted in the frame F connected to and supported by the shifting mechanism H, as in the said Rogers application; and the auxiliary magazines E are mounted in the frame G connected to and supported by the shifting mechanism L, which is of substantially the same construction. The respective shifting means H and L are manually operated from the same handle J¹ carried by the arm J upon the shaft K.

The shaft K carries the sleeve K¹ and the bevel pinion K² thereon, which pinion meshes into the bevel pinion L² connected to the shaft L¹, which actuates the auxiliary shift mechanism L. The sleeve K¹ is splined to the shaft K, so as to be capable of longitudinal movement thereon, and is normally held in retracted position by the engagement therewith of one arm of the elbow lever M connected to the spring M¹. In this relation of the parts (see Fig. 1), the pinion K² engages the pinion L², so that the rotation of the shaft K by the arm J and handle J¹ effects the actuation of the mechanism L and the shifting of the auxiliary magazines E in the manner well understood in the art.

The sleeve K¹ is formed at its end with a

clutch member K³ adapted to engage the clutch member H³ connected to the shaft H¹, which actuates the main shift mechanism H. In the normal position of the parts already described, the clutch is open, and in order to close it and thus effect an operative connection to the shift mechanism H, it is necessary to move the sleeve K¹ longitudinally, to the position shown in Fig. 4, which movement simultaneously disengages the pinion K² from the pinion L². The means for effecting this result comprise the longitudinally slideable rod M² connected at one end to the lever M, and bearing at its other end against the plate J², which is pivotally connected at J³ to the arm J. The operating handle J¹ is mounted in the arm J so as to be longitudinally movable with relation thereto, and is connected at its inner end with the plate J². When it is desired to disconnect the auxiliary shifting means, and to connect the main shifting means, the handle J¹ is moved to the full line position in Fig. 4, thus moving the rod M², lever M and sleeve K¹, and effecting the engagement of the clutch member K³ with the clutch member H³.

The means for locking the respective series of magazines D and E in operative position are substantially similar to those set forth in the said Rogers application and comprise longitudinally movable bars N adapted to engage in the notches N¹, formed in the sides of the respective frames F and G. Normally the bar N is held in locking engagement with the proper notches N¹ by a spring, not shown herein. In the present instance, both sets of bars N are controlled from the operating handle J¹. The bars N corresponding to the main magazines D are connected to the arms N² mounted upon the shaft O (see Fig. 7), which is rotated by the link M³ connected to the outer end of the previously mentioned elbow lever M. In the normal position of the parts, when the pinions K² and L² are in engagement and consequently the auxiliary shift mechanism L is in operative condition, at which time the elbow lever M is in its retracted position, the frame F of the main magazines D is held against movement by the engagement of the bars N in the notches N¹. The movement of the sleeve K¹ to disengage the pinions K² and L², and to engage the clutch members K³ and H³, as previously set forth, is effected by the inward movement of the plate J² and rod M² and the pivotal movement of the elbow lever M, and due to the consequent action of the connected link M³, the main magazines D are simultaneously unlocked and placed in readiness to be shifted. Similarly, the locking bars N of the frame G of the auxiliary magazines E are controlled by the arms N² mounted upon the sleeve O¹ (see Fig. 7), which is rotated by the link N³, lever N⁴, and rod N⁵, connected at one end to the lever N⁶,

and bearing at its other end against the plate J^2 at a point thereon on the opposite side of its pivotal connection J^3 from that engaged by the previously mentioned rod M^2 . When the parts are in the position shown in Fig. 4, namely, with the main shift mechanism H connected and the auxiliary shift mechanism L disconnected, the bars N are in engagement with the notches N^1 of the frame G and thus lock the auxiliary magazines E against shifting. Their unlocking is effected by the movement of the handle J^1 and pivotal plate J^2 to their extreme outward position, as shown by dotted lines in Fig. 4, thereby moving the rod N^5 inwardly, and through the lever N^4 depressing the link N^3 , which through the described connections frees the notches N^1 of the frame G from the locking engagement of the bars N . This movement of the handle J^1 and plate J^2 also permits the spring M^1 to act, and effects the consequent breaking of the clutch K^3 , H^3 , and the reengagement of the pinions K^2 and L^2 . In other words, the extreme inward movement of the handle J^1 and plate J^2 effects the operative connection of the shift mechanism H and the simultaneous unlocking of the magazines D . Similarly, the extreme outward movement of the handle J^1 and plate J^2 effects the operative connection of the shift mechanism L and the simultaneous unlocking of the magazines E . The parts are so formed and arranged that when the handle J^1 and plate J^2 are in their intermediate or normal position, as shown in Fig. 1, both sets of magazines D and E are locked against shifting.

Fig. 3 illustrates the manner in which any one of the magazines D may be brought into simultaneous operation with any one of the magazines E . In diagram A, the intermediate magazine D and the lower magazine E are shown at the operative level, this being represented by the line $a-a$. In diagram B, the upper magazine D and the lower magazine E are thus indicated. In diagram C, the upper magazine D and the upper magazine E are so shown. Fig. 5 illustrates the employment of a plurality of auxiliary magazines E in connection with a single main magazine D^1 , as distinguished from a plurality of main magazines such as shown in Fig. 3, diagram A illustrating the upper magazine E as simultaneously operative with the magazine D^1 , and diagram B illustrating the lower magazine E in the same relation.

Fig. 6 shows the employment of a plurality of short auxiliary magazines E^1 , a single one of which is illustrated in my previous application for Letters Patent, Serial No. 789,026, filed September 10, 1913. Three such magazines are shown, arranged to be shifted so that the selected one will be in operative relation to the fixed conductor T , which receives the matrices from the chan-

nel entrance S , in substantially the manner described in the said application.

As previously stated, I have shown my invention only in preferred form and by way of example, and as applied to the specific form of machine indicated, but obviously, many other modifications and alterations therein, and in its mode of application, will suggest themselves to those skilled in the art, without departure from its scope. 75

Having thus described my invention, its construction and mode of operation, what I claim and desire to secure by Letters Patent of the United States, is as follows:

1. In a typographical machine, the combination of distributing mechanism, and two series of magazines arranged side by side in the machine, each series being movable independently of the other to bring one or another of its magazines into operative relation to the distributing mechanism; whereby any magazine of one series may be used conjointly with any magazine of the other series. 80

2. In a typographical machine, the combination of assembling mechanism, and two series of magazines arranged side by side in the machine, each series being movable independently of the other to bring one or another of its magazines into operative relation to the assembling mechanism; whereby any magazine of one series may be used conjointly with any magazine of the other series. 95

3. In a typographical machine, the combination of distributing mechanism, two series of magazines arranged side by side in the machine, each of said magazines having a series of matrix channels, and means whereby the distributing mechanism may be connected to any selected pair of magazines of the two series at will. 100

4. In a typographical machine, the combination of assembling mechanism, and two series of magazines arranged side by side in the machine, and means whereby the assembling mechanism may be connected to any selected pair of magazines of the two series at will. 110

5. In a typographical machine, the combination of two series of magazines in the machine, and a keyboard mechanism for each series adapted to be connected with one or another of the magazines therein; whereby any magazine of one series may be used simultaneously with any magazine of the other series. 115

6. In a typographical machine, the combination of a plurality of magazines, two keyboard mechanisms, and means whereby each keyboard mechanism may be connected to different magazines of said plurality; whereby different pairs of magazines may be used simultaneously. 125

7. In a typographical machine, the combination of distributing mechanism, a chan- 130

neled magazine of full length arranged in operative relation thereto, a plurality of magazines of less than full length and each having a series of matrix channels, and 5 means whereby one or another of the magazines of said plurality may be operatively connected with the distributing mechanism.

8. In a typographical machine, the combination of distributing mechanism, a magazine of full length in operative relation thereto, a plurality of magazines of less than full length, each having a series of matrix channels, and movable to bring one or another thereof into operative position, and a conductor having a corresponding series of channels to connect the distributing mechanism with the selected magazine of said plurality. 10

9. In a typographical machine, the combination of two series of magazines arranged side by side in the machine, and each movable independently of the other to effect a change from one magazine to another therein; whereby different pairs of magazines 20 may be selected for conjoint use. 25

10. In a typographical machine, the combination of a common distributing mechanism, and two series of magazines, each series being movable independently of the other to bring one or another of its magazines into operative relation to the distributing mechanism; whereby any magazine of one series may be used conjointly with any magazine of the other series. 30 35

11. In a typographical machine, the combination of a magazine entrance, a plurality of magazines remote therefrom and movably mounted so that any selected one may be brought into operative position, and an intermediate conductor to connect the entrance with the operative magazine, the said conductor being removable at will to permit the entrance to coöperate directly with other magazines. 40

12. In a typographical machine, the combination of a magazine entrance, a plurality of magazines of less than normal length and movably arranged so that any selected one may be brought into operative position, and 50 an intermediate conductor to connect the magazine entrance with the operative magazine, the said conductor being removable at will to permit the entrance to coöperate with magazines of full length. 45

13. In a typographical machine, the combination of two series of movable magazines, a locking device for each series, and a common controlling means for both locking devices. 55

14. In a typographical machine, the combination of two series of movable magazines, separate shifting mechanism therefor, locking devices for each series, and a common means for controlling the locking devices and shifting mechanism of both series. 60 65

15. In a typographical machine, the combination of two series of movable magazines, locking devices for each series, shifting mechanism for each series, common operating means adapted to be connected alternately to said shifting mechanisms, and means whereby the connection of the operating means to the shifting mechanism of one series will effect the release of the corresponding locking devices and the operative 70 75 engagement of the locking devices of the other series.

16. In a typographical machine, the combination of two series of movable magazines, a locking device for each series, and 80 a common controlling means which, when moved in one direction, will effect the release of one of the locking devices, and when moved in the opposite direction, will effect the release of the other locking device. 85

17. In a typographical machine, the combination of two series of movable magazines, locking devices for each series, shifting mechanism for each series, common operating means adapted to be connected alternately to said shifting mechanisms, and means whereby the connection of the operating means to the shifting mechanism of one series will effect the release of the corresponding locking devices. 90 95

18. In a typographical machine, the combination of two series of magazines arranged side by side in the machine, separate shifting mechanism for each series, and common operating devices adapted to be connected 100 to one or the other of the two shifting mechanisms.

In testimony whereof I have affixed my signature in presence of two witnesses.

DAVID S. KENNEDY.
